DESIGN FOR A HOLDER FOR HABIT FORMING CHARTS

Gladys Bales, Kansas City, Mo.

Application October 25, 1943, Serial No. 111,497

Term of patent 3½ years

To all whom it may concern:

Be it known that I, Gladys Bales, a citizen of the United States, residing at Kansas City, in the county of Jackson and State of Missouri, have invented a new, original, and ornamental Design for a Holder for Habit Forming Charts, of which the following is a specification, reference being had to the accompanying drawing, forming a part thereof.

Fig. 1 is a front view of the holder for habit forming charts, showing my new design; and

Fig. 2 is an edge elevational view thereof.

I claim:

The ornamental design for a holder for habit forming charts, as shown.

GLADYS BALES.
